(57) **CLAIM**

The ornamental design for a jar lid with a closable spout, as shown and described.

DESCRIPTION

FIG. 1 is a top-side perspective view of a jar lid with a closable spout showing my new design, wherein the spout cover of the jar lid is disposed in a closed position;

FIG. 2 is a top plan view of the lid shown in FIG. 1;

FIG. 3 is a bottom plan view of the lid shown in FIG. 1;

FIG. 4 is a right side elevational view of the lid shown in FIG. 1;

FIG. 5 is a left side elevational view of the lid shown in FIG. 1;

FIG. 6 is another top-side perspective view of the lid shown in FIG. 1, wherein the jar lid is illustrated together with an unclaimed jar and a jar band in an assembled state;

FIG. 7 is yet another top-side perspective view of the lid shown in FIG. 1, wherein the jar lid is illustrated together with an unclaimed jar and a jar band in an exploded state;

FIG. 8 is still another top-side perspective view of the lid shown in FIG. 1, wherein the spout cover of the jar lid is disposed in an open position, and wherein the jar lid is illustrated together with an unclaimed jar and a jar band in an assembled state;

FIG. 9 is yet another top-side perspective view of the lid shown in FIG. 1, wherein the spout cover of the jar lid has been removed, and a sectional cutting-plane line 10-10 is shown thereon;

FIG. 10 is a cross-sectional view of the lid shown in FIG. 1, wherein the spout cover of the jar lid has been removed, and wherein the jar lid has been cut in the direction of the cutting-plane line 10-10 in FIG. 9;

FIG. 11 is a top perspective view of the spout cover of the jar lid with a closeable spout, shown removed from the lid for clarity of disclosure; and,

FIG. 12 is a bottom perspective view of the spout cover of the jar lid with a closeable spout, shown removed from the lid for clarity of disclosure.

The broken line portions of the drawing figures are included to show unclaimed subject matter only and form no part of the claimed design.
